JOSEPH F. KERNAN AND WILLIAM J. OWENS, OF UTICA, NEW YORK.

FIRE-POT FOR STOVES AND FURNACES.

1,140,464.

Specification of Letters Patent. Patented May 25, 1915.

Application filed October 6, 1909, Serial No. 521,197. Renewed October 30, 1914. Serial No. 869,487.

To all whom it may concern:

Be it known that we, JOSEPH F. KERNAN and WILLIAM J. OWENS, citizens of the United States, residing at Utica, in the county of Oneida and State of New York, have invented new and useful Improvements in Fire-Pots for Stoves and Furnaces, of which the following is a specification.

This invention relates to fire-pots for stoves and furnaces employing the so called "hot blast", or over draft, in which heated air is admitted to the combustion chamber to promote and increase the combustion, and has for its particular object to improve the construction and operation and to render the fire-pot stronger and more durable.

The essential features of furnaces of this type consist in providing air passages in or immediately adjacent to the fire-pot in such manner that the air passing there through will become heated to a considerable degree before it is admitted to the combustion chamber above the grate to commingle with and promote the complete combustion of the products. Great difficulty, however, has been experienced in the production of a fire-pot provided with air passages arranged efficiently to heat the air without material weakening of the fire-pot and danger of breaking during expansion and contraction. Efficiently to heat the air and deliver it in its properly heated state, various constructions of fire-pots have been proposed with interior or exterior tubular columns, specially arranged and formed and communicating with the combustion chamber through apertures in the fire-pot wall. These structures have proved impracticable and liable to crack; where the columns have been arranged on the exterior of the fire-pot, the fire-pot wall is in direct contact with the heat of combustion, to expand and contract while the columns remaining comparatively cool will crack; where on the interior, the columns are in contact with the combustion, but the portion of the fire-pot wall covered by the columns is not in contact, therefore there will be irregular expanding and contracting and danger of breaking.

We believe we have overcome all the objections by the particular structure here shown and our invention has in view to remedy these defects in a manner to produce a practicable and durable fire-pot which will accomplish the desired results. These particular features of construction are de-

scribed and shown in the accompanying drawing in which the reference numerals of the description indicate corresponding parts in all the figures.

In the drawing Figure 1 is a sectional view of a furnace having a fire-pot embodying our invention. Fig. 2 is a plan view of our improved fire-pot showing a portion of the upper half broken away.

In the figures A indicates the fire-pot provided with the usual groove 3 on its upper edge to receive the corrugated dome 5 of the combustion chamber having ribs 6, resting thereon.

8 is the casing commonly of galvanized iron, inclosing the usual grates 9, ash pit 10, radiator 11 etc.

Our improved fire-pot A desirably may be formed substantially cylindrical as shown 75 and made in two sections, lower section 12 being flanged at 13 to accommodate the upper section 14 resting thereon; the sections are provided with the usual radially disposed ribs 15, and to supply the desired 80 heated air blast within the combustion chamber 16 are formed air passages 18. In accordance with our invention these passages are arranged on the interior of the fire-pot; the pot for this purpose is formed 85 integrally to provide on its interior a series of opposing or right and left ribs 20-20' forming the air passages 18 on the inside of the pot and spaced to leave the communicating slots 21 to the combustion chamber 90 through which the air is supplied. By so forming the air spaces or flues by means of these independent ribs on the interior of the fire-pot proper, the heating and distribution of the air is accomplished in an 95 effective manner without impairing the durability of the pot, as by this arrangement the ribs are free to expand and contract substantially independent of the fire-pot wall and all parts of the fire-pot wall are heated 100 with substantial equality, so that expansion and contraction thereof is substantially uniform.

As shown the ribs may be inclined and curved in form providing an air passage or 105 flue wider at the bottom than at the top to prevent their becoming clogged up with ashes and clinkers the ashes being permitted to drop freely into the ash pit. Ribs may be provided to form any number of air passages and spaced to provide any size of slot desired, a desirable arrangement being

here shown consisting of sixteen of such passages arranged equidistant around the interior of the pot with communicating slots of about $1/16$ " to the combustion chamber.

5 We have thus produced an improved fire-pot successfully embodying the features of this type of furnace in a manner contributing to the efficiency of the air supply, while in no way impairing or weakening the fire-pot, uniform expansion and contraction being permitted at all times.

Having thus described our invention, what we claim is:

15 1. A fire-pot having a wall of substantially uniform thickness and extending in a substantially uniform curve throughout its entire periphery, and having small, integral, supplementary, curved ribs inwardly projecting from its interior surface and re-

20 versely arranged with their edges adjacent and suitably spaced to form air passages within the ribs and longitudinal slots from the air passages to the combustion chamber, said air passages being larger at the bottom, 25 and gradually diminishing toward the top, substantially as described and shown.

2. A sectional fire pot composed of circular sections each having a wall of substantially uniform thickness and having small 30 integral, supplementary, curved ribs inwardly projecting from its interior surface and reversely arranged with their edges adjacent and suitably spaced to form air passages within the ribs and longitudinal slots 35 from the air passages to the combustion chamber, said air passages being larger at the bottom and gradually diminishing toward the top and the air passages of the lower section communicating with the upper

section to form continuous passages, substantially as described.

3. A fire-pot having a wall of substantially uniform thickness and extending in a substantially uniform curve throughout its entire periphery, and having small, supplementary, curved ribs inwardly projecting from its interior surface and reversely arranged with their edges adjacent and suitably spaced to form air passages within the ribs and longitudinal slots from the air passages to the combustion chamber, said air passages being larger at the bottom and gradually diminishing toward the top, substantially as described and shown.

4. A sectional fire-pot composed of circular sections each having a wall of substantially uniform thickness and having small, supplementary, curved ribs inwardly projecting from its interior surface and reversely arranged with their edges adjacent and suitably spaced to form air passages within the ribs and longitudinal slots from the air passages to the combustion chamber, said air passages being larger at the bottom and gradually diminishing toward the top and the air passages of the lower section communicating with the upper section to form continuous passages, substantially as described.

In testimony whereof we have signed our names to this specification in the presence of two subscribing witnesses.

JOSEPH F. KERNAN.
